[57] CLAIM

The ornamental design for a golf swing practice device, as shown and described.

DESCRIPTION

FIG. 1 is an elevational view of the golf swing practice device showing my new design, the broken lines illustrating a golfer using the device are for illustrative purposes only and form no part of the claimed design;
FIG. 2 is a perspective view of one side as viewed from the bottom thereof; and,
FIG. 3 is a perspective view of the opposite side thereof as viewed from the top.
